WILBUR H. ARMACOST, OF NEW YORK, N. Y., ASSIGNOR TO THE SUPERHEATER COMPANY, OF NEW YORK, N. Y.

HEAT EXCHANGER

Application filed March 9, 1927. Serial No. 173,904.

My invention relates to heat exchangers and has specific reference to the general type of exchanger in which a transfer of heat is effected between non-contacting fluid media.

In heat exchange devices such as boilers, oil stills, evaporators and similar apparatus, it is often highly desirable from a manufacturing standpoint to use sets of certain so-called "standard" dimensions. These types of structures are further often designed for service wherein the operating conditions may be materially changed after the unit is placed in service. For example, in the case of boilers and oil stills, the type of fuel used may be changed, and in the case of stills and chemical apparatus the character of the liquid to be heated or cooled may vary within wide limits.

The present invention has for its principal object the provision of a form of heat exchanger which will enable widely varying operating conditions to be met by a structure of standard form and dimensions. A further object is the provision of a form of heat exchanger which after being assembled may have its characteristics so altered that it may be rendered suitable for operating conditions other than those for which it was originally designed. More specifically, the object of the invention is the provision of apparatus in which a plurality of heat exchange tubes are placed in the confined path of a heat absorbing or rejecting fluid in such a manner that the free flow area for said fluid, and consequently its velocity, may be varied in any given passage. A still further object of the invention is the accomplishment of the above objects by the use of heat exchange elements of a type wherein the free flow area past such elements through any given passage may be varied by the rotation of said elements around their longitudinal axes. Further and more detailed objects of the invention together with the advantages to be derived from its use will become apparent from a perusal of the ensuing detailed description of preferred embodiments of the invention which I have illustrated in the accompanying diagrammatic drawings, in

which Figs. 1a, 1b, and 1c are transverse sections taken through the same apparatus in different positions. Fig. 2 is a longitudinal section taken through one form of apparatus embodying the invention, Fig. 3 is a section similar to Fig. 2 showing apparatus embodying another form of the invention, and Fig. 4 is a fragmentary elevation on an enlarged scale of part of the structure shown in Fig. 3.

Referring now to Fig. 1a, I have shown diagrammatically a passage 1, defined by walls 2, and adapted to convey absorbing or rejecting fluid in either of the directions indicated by the arrow in the figure.

Located transversely of the flow of fluid through passage 1 are a plurality of fluid carrying elements, each of which comprises a plurality of individual pipes 3 which are joined at their ends to form single end portions 4, the latter being secured in suitable headers, connected by return bends.

The specific arrangement of these elements with respect to their spacing in rows, etc., may be widely varied within the scope of the invention, but for purposes of illustration I have shown these elements arranged in horizontal rows, with the elements staggered with respect to each other vertically. In Fig. 1a I have shown the elements arranged with the individual pipes 3 set horizontally with respect to each other in the individual units, and it will be readily apparent from the figure that with this arrangement, the minimum free flow area is provided for the fluid passing these elements. In Fig. 1b I have shown the same apparatus with the elements rotated about their longitudinal axis substantially 45 deg. from the position shown in Fig. 1a, and it will be evident that with this arrangement the free flow area round these elements through passage 1 has been materially increased. In Fig. 1c the same apparatus is shown with the elements rotated 90 deg. from the position shown in Fig. 1a, and it will be seen that in this position the maximum free flow area is provided past the elements. It will further be apparent that this change in the free flow area through the passage 1 is effected without in any way necessitating a change in the structure of the apparatus as a

whole, and that any desired variation in the free flow area through a given structure may be readily varied from the minimum, as established by the position shown in Fig. 1a, to the maximum, as established by the position of the elements in Fig. 1c, merely by the rotation of the elements about their longitudinal axes.

While I have shown, for purposes of illustration, elements having the minimum number of individual pipes, and with the pipes of the same diameter, it will be readily apparent to those skilled in the art that elements having three or more individual pipes, 10 of the same or different diameters, joined to form single end sections may be utilized in precisely the same manner as the elements herein illustrated.

In Fig. 2 I have shown a section taken 20 longitudinally of the elements, in which the passage 1 is defined by the side walls 2 and headers 30. The flow of fluid through the passage 1 is at right angles to the plane of the paper, and in this instance the units are 25 formed with single cylindrical ends 4 adapted to be rolled or otherwise suitably secured in the inner walls 5 of headers 30, the latter being provided with suitable handholes or cover plates 6. With the element ends formed 30 in this manner the apparatus is not adapted to be changed readily after having been originally assembled, but the invention enables an apparatus of this character and of a certain standard size to be adapted to various 35 types of service, because of the various positions in which the elements may be initially set.

In Fig. 3 I have shown the apparatus, in 40 a section similar to Fig. 2, constructed in a form suitable for change or adjustment of the units after the apparatus as a whole has been assembled. In this form the element ends 4 are provided at their ends with upset or other suitably formed rings 7, the latter 45 being ground to form suitable seats, preferably spherical or conical. Header boxes 8 seat against rings 7 and are held in place by means of the studs 10, which pass through suitable bosses on the header boxes and are 50 screwed into ears formed on the clamp rings 9 which seat against the opposite faces of rings 7.

It will be evident from an inspection of the figure that by simply loosening the connections between the header boxes 8 and the element ends 4 that the elements may be freely 55 rotated to any desired position and then again clamped in position between the header boxes to secure the necessary fluid-tight 60 joints. While in Fig. 2 I have shown the elements permanently secured in headers imposing parallel flow through the elements, and in Fig. 3 I have shown the elements adjustably mounted between header boxes imposing series flow through the tubes, it is to be 65

understood that the manner of securing the elements, that is, either permanently or adjustably, is not in any way dependent upon the manner in which the elements may be assembled with respect to the fluid flow therethrough. It is to be noted, however, that the type of end joint shown in Fig. 3 is not well suited for use in connection with headers receiving a large number of tubes, such as headers 30 in Fig. 2, for if the adjustable 70 type of element is used between such headers, it will be apparent that all of the elements joining any two headers must be of exactly the same finished overall length if tight joints are to be secured, and that any unequal 75 expansion of elements between such headers would tend to produce leaky joints. For these reasons, I prefer to use individual header boxes such as those shown at 8 in Fig. 3, at least at one end of the elements, as far as 80 possible where the adjustable type of element is used.

As mentioned above, this type of structure is particularly adaptable for use in boilers, oil stills and similar apparatus where the 90 fluid carried by the elements is under high pressure, and for this reason, I prefer to use integral elements of the type illustrated, in which the end sections 4 of the elements are formed integrally from pipes 3, as by the 95 forging process shown in Patent No. 1,169,209 issued January 25, 1916, to C. H. True and N. T. McKee, followed by the initial steps of the process shown in Patent No. 1,155,110 issued September 28, 1915, to 100 the same inventors. The end sections 4 of the elements may, however, equally well be made by welding or, in cases where the elements are not to be subjected to extreme internal pressures, the elements may, if desired, be built up by the use of individual pipes threaded or otherwise suitably secured in Y fittings, the bottom portions of which may be extended and either expanded into suitable headers or formed with suitable end seats for the purpose of adjustable clamping. 110

From the foregoing description it will be apparent that the present invention may be applied in a wide variety of specific forms and arrangements. The illustrative examples of the invention herein disclosed are, therefore, to be taken as illustrative only and not limiting in sense, and the scope of the invention is to be limited only by that of the appended claims. 115

I claim:

1. In apparatus of the class described, the combination with a passage adapted to convey a heat absorbing or rejecting fluid, of a plurality of heat exchanging elements disposed in said passage at an angle to the line of fluid flow therethrough, each of said elements comprising end sections symmetrical with respect to the longitudinal axis of the element and an intermediate section connect- 120 125 130
